UNITED STATES PATENT OFFICE.

ROBERT KENNEDY DAWSON, OF GUELPH, ONTARIO, CANADA.

DESIGN FOR A THREE-WHEELED CAR FOR CHILDREN.

52,209.

Specification for Design.

Patented July 23, 1918.

Application filed January 14, 1918. Serial No. 211,897. Term of patent 7 years.

To all whom it may concern:

Be it known that I, ROBERT KENNEDY DAWSON, a subject of the King of Great Britain, and a resident of the city of Guelph, in the county of Wellington, in the Province of Ontario, Canada, have invented a new, original, and ornamental Design for a Three-Wheeled Car for Children, of which the following is a specification, reference being had to the accompanying drawing, forming part thereof.

The figure represents a perspective view showing the design of my three-wheeled car.

Copies of this patent may be obtained for five cents each, by addressing the "Commissioner of Patents, Washington, D. C."

I claim:

The ornamental design for a three-wheeled car for children, as shown, having a two part body with the parts connected by an inverted arch member to produce an ornamental effect.

ROBERT K. DAWSON.
